UNITED STATES PATENT OFFICE.

THEOPHILE BOUDREAU, OF LABADIEVILLE, LOUISIANA.

STUBBLE-SHAVER AND CANE-SCRAPER.

1,068,305.

Specification of Letters Patent.

Patented July 22, 1913.

Application filed February 4, 1913. Serial No. 746,220.

To all whom it may concern.

Be it known that I, THEOPHILE BOUDREAU, citizen of the United States, residing at Labadieville, in the parish of Assumption 5 and State of Louisiana, have invented new and useful Improvements in Stubble-Shavers and Cane-Scrapers, of which the following is a specification.

My present invention pertains to stubble 10 shavers, and consists in the peculiar machine, hereinafter described and claimed, constructed with a view to being used to advantage in the shaving of a cane stubble crop and also in the scraping of a plant- 15 cane crop.

The machine is also adapted to accomplish both functions stated at the same time, if desired.

In the drawings, accompanying and forming 20 part of this specification: Figure 1 is a side elevation of the machine, constituting the best practical embodiment of my invention that I have as yet devised; the working parts being shown by full and 25 dotted lines in different positions. Fig. 2 is a plan of the lower part of the rear portion of the machine. Fig. 3 is a front elevation of the machine.

Similar numerals of reference designate 30 corresponding parts in all of the views of the drawings.

Among other features my novel machine 35 comprises spaced runners 1 and a longitudinal-central beam 2, disposed in a horizontal plane considerably above that of the 40 runners and having at its forward end suitable means 3 for the attachment of draft animals. The beam 2 is supported in the relative position stated by metallic supports 45 4, fixed at their ends to the runners and at intermediate points of their lengths to the beam. On the rear portion of the beam 2 is fixed a support 5 bearing a driver's seat 6, and on the rear support 4 are fixed foot- 50 rests 7. It will also be noticed that the beam 2 is equipped with a fixed standard 8 and a rigid brace 9 therefor, and that behind 55 said standard a curvilinear and apertured bar 10 is fixed to and rises from the beam. Fulcrumed at 11 on the standard 8 is a hand lever 12, equipped with a detent 13 60 designed to enter apertures in the bar to adjustably fix the lever thereto, and interposed between and connected to the forward 65 arm of the lever and the beam 2 is a retractile spring 14, calculated to assist in the

upward movement of the rear arm of the lever and the weight that is carried by said arm, as hereinafter described. Braces 15 are extended between and connected to the 60 runners 1 and the forward upright 4, as shown.

16 is a vertically-disposed and longitudinal-central steel disk, having a knife edge, and designed to form a furrow incidental to 65 the forward movement of the machine.

17 is a V-shaped scraper having a blunt edge and designed to scrape plant-cane as well as remove cut stubbles from the row.

18—18 are horizontally-disposed steel 70 shaving blades, having forward knife edges, and adapted to shave stubble, and 19 is a vertically movable sub-frame, while 20—20 and 21—21 are lower and upper, longitudinal, vertically-swinging arms connected adjacent their forward ends to the side portions of the forward upright 4 and also connected near their rear ends to the side portions of the sub-frame 19. The disk 16 is mounted in and carried by a hanger 22 connected to and depending from the transverse portion of the sub-frame 19, and curved forwardly and downwardly from 75 said sub-frame portion, as best shown in Fig. 1. The hanger 22 is preferably ex- 80 tended rearwardly from the sub-frame 19 to form a beam 23, and to said beam is connected, preferably by a shackle 24, a standard 25 that is fixed with respect to 85 and rises from the blunt-edge scraper 17. 90 The shaving blades 18 are fixed to and carried by the depending portions of the sub-frame 19.

Connected to and rising from the sub-frame 19 is a bar 26 which bar is preferably 95 connected to the rear arm of the lever 12 in an adjustable manner, as shown. From this it will be readily appreciated that when the lever 12 is swung to carry its rear arm upwardly, the disk 16, scraper 17 and 100 shaver blades 18 will be simultaneously raised, as indicated by the dotted lines in Fig. 1. The spring 14 will assist in the said upward movement of the rear arm of the lever and the parts connected therewith, so 105 that the expenditure of but little effort on the part of the driver is required. On downward movement of the rear arm of lever 12, the scraper 17, the disk 16 and shaver blades 18 will be simultaneously de- 110 pressed and carried to the lower positions.

The facility with which the sub-frame 19

can be raised and lowered by the driver incidental to the progress of the machine will be appreciated as an important advantage when it is stated that because of the uneven surface of the ground the sub-frame 19 must be repeatedly raised and lowered so as to assure the stubbles being shaved level with the ground.

The vertically swinging arms 20 and 21 serve to hold the sub-frame 19 at right angles to the runners 1, irrespective of the height of the sub-frame, and in that way assure the scraper 17 and the shaving blades 18 being always parallel to the runners and the surface of the field. It will also be noted that the lower arms 20 are extended rearwardly of the sub-frame 19 and are arranged and adapted to move vertically at the inner sides of the side portions of the rear support 4, this in order to enable said lower arms 20 to prevent lateral movement of the sub-frame 19 and the parts carried thereby.

The disk 16 during the operation of the machine forms an opening for the apex of the scraper 17 to follow in, and also serves to cut through or clear any obstruction which might tend to bend the apex or point of said scraper 17.

My novel machine is adapted to be used to shave and scrape at the same time, or the shaving can be accomplished at one time and the scraping at another time.

It will also be appreciated that the machine is adapted to be handled to advantage by a single man and that it is calculated to assure uniform growth of sugar cane.

Having described my invention, what I claim and desire to secure by Letters-Patent, is:

1. In a machine for the purpose described, the combination of runners, a longitudinal-central beam located in a horizontal plane above that of the runners, supports fixed to the runners and the beam, a standard fixed to and rising from the beam, a hand lever fulcrumed at an intermediate point in its length on the standard, a retractile spring connecting the forward arm of said lever and the forward portion of the beam, means for adjustably fixing the lever with respect to the beam, a vertically-movable sub-frame disposed below the beam and having a transverse portion and depending side portions, a rigid upright fixed to the transverse portion of the sub-frame and pivotally connected to the rear arm of the lever, upper and lower vertically-swinging arms pivoted to the side portions of the forward support and also pivoted to the side portions of the sub-frame; the lower arms being extended rearwardly of the sub-frame and arranged to bear in their vertical movements against the inner sides of the side portions of the rear support, a hanger fixed to and extending

ing downward and forward from the transverse portion of the sub-frame, a vertical longitudinal-central disk carried by said hanger, and shaving blades carried by the depending portions of the sub-frame and disposed parallel to the runners.

2. In a machine for the purpose described, the combination of runners, a longitudinal-central beam located in a horizontal plane above that of the runners, supports fixed to the runners and the beam, a standard fixed to the runners and the beam and rising from the latter, a hand lever fulcrumed at an intermediate point in its length on the standard, a retractile spring connecting the forward arm of said lever and the forward portion of the beam, means for adjustably fixing the lever with respect to the beam, a vertically-movable sub-frame disposed below the beam and having a transverse portion and depending side portions, a rigid upright fixed to the transverse portion of the sub-frame and pivotally connected to the rear arm of the lever, upper and lower vertically-swinging arms pivoted to the side portions of the forward support and also pivoted to the side portions of the sub-frame; the lower arms being extended rearwardly of the sub-frame and arranged to bear in their vertical movements against the inner sides of the side portions of the rear support, a hanger fixed to and extending downward and forward from the transverse portion of the sub-frame and forming a beam, a vertical longitudinal-central disk carried by said hanger, shaving blades carried by the depending portions of the sub-frame and disposed parallel to the runners, and a V-shaped scraper disposed below and rigidly connected with the said beam on the sub-frame.

3. In a machine for the purpose described, the combination of a main frame, a vertically-movable sub-frame, vertically-movable means connected with the sub-frame and coöperating with the main frame to prevent lateral movement of the sub-frame, a disk and stubble-shaving means carried by said sub-frame, means for raising the sub-frame, and means for adjustably fixing the sub-frame against downward movement.

4. In a machine for the purpose described, the combination of a main frame, a vertically-movable sub-frame connected with the main frame, a disk, stubble-shaving means and cane-scraping means carried by and movable vertically with the sub-frame, vertically-movable means connected with the sub-frame and the main frame and coöperating with the latter to prevent lateral movement of the sub-frame, means on the main frame for raising the sub-frame, and means for adjustably fixing the sub-frame against downward movement.

5. In a machine for the purpose described, the combination of a main frame having runners, a vertically movable sub-frame, a disk, stubble-shaving means and cane-scraping means carried by the sub-frame, means for raising the sub-frame, means for adjustably fixing the main frame against downward movement, and means for preventing lateral movement of the sub-frame and for maintaining the shaving means and the scraping means at all times in parallel relation to the runners.
- 10 6. In a machine for the purpose described, the combination of a main frame having
- runners, a vertically-movable sub-frame, a disk and stubble-shaving means on the sub-frame, means for raising the sub-frame, and means for preventing lateral movement of the sub-frame and for maintaining the shaving means at all times in parallel relation 20 to the runners.

In testimony whereof I have hereunto set my hand in presence of two subscribing witnesses.

THEOPHILE BOUDREAU.
